UNITED STATES PATENT OFFICE.

EUGENE CLAYTON BERNHEIM, OF WASHINGTON, DISTRICT OF COLUMBIA,
ASSIGNOR TO CARL PETERSEN, OF SAME PLACE.

DESIGN FOR A SPOON.

SPECIFICATION forming part of Design No. 22,093, dated January 3, 1893.

Application filed December 2, 1892. Serial No. 453,889. Term of patent 3½ years.

To all whom it may concern:

Be it known that I, EUGENE CLAYTON BERNHEIM, a citizen of the United States, residing at Washington, in the District of Columbia, ³⁵ have invented and produced a new and original Design for Spoons; and I do hereby declare the following to be a full, clear, and exact description of the same, reference being had to the accompanying drawings, forming a part ⁴⁰ thereof.

My invention relates to a new and original design for the handles and bowls of spoons, and consists in the configuration and ornamentation, as will be hereinafter described ⁴⁵ and claimed.

In the drawings, Figure 1 is the front or obverse face of the spoon. Fig. 2 is the reverse face of same.

The extremity or end of the handle consists of a bust of Grover Cleveland, under which is an ornamental scroll having a plane face to receive any suitable inscription. The continuation or narrow part of the handle extending to the bowl, is provided with a ⁵⁰ longitudinally arranged word-panel, and is joined or connected to the bowl with an ornamental scroll, from which depends a tassel, and double looped curtains, the latter being draped on opposite sides of the upper portion ⁵⁵ of the interior of the bowl, and each provided in its broad portion with a space to receive

any suitable inscription. These curtains serve as a framing for a representation or front view of the White House or Presidential Mansion located within the central portion of the bowl; and beneath the representation of the White House is a space for the inscription of any desired or suitable words, or numerals. The reverse of the spoon handle represents an irregular contour (the upper portion of which is broadest), which conforms to the outline or contour of the face or obverse, and affords a longitudinal plane surface of irregular shape, adapted to have inscribed thereon words or numerals arranged ⁴⁰ in any desired or suitable manner.

The object of my invention is a spoon, commemorative of the Presidential candidacy of Grover Cleveland, and its essential features consist in its shape and ornamentation, as ⁵⁰ shown in the drawings accompanying this specification.

Having thus described my invention, I claim

The design for a spoon as hereinbefore ⁵⁵ shown and described.

In testimony whereof I affix my signature in presence of two witnesses.

EUGENE CLAYTON BERNHEIM.
